UNITED STATES PATENT OFFICE.

JAMES J. SUNDAY, OF DETROIT, MICHIGAN, ASSIGNOR, BY MESNE ASSIGNMENTS, TO KELCH VENTILATING HEATER COMPANY, A CORPORATION OF MICHIGAN.

HEATER FOR AUTOMOBILES.

Application filed January 25, 1926. Serial No. 83,733.

This invention relates generally to heaters for automobiles.

One of the essential objects of the invention is to provide the usual exhaust muffler 5 of an automobile with a jacket in which fresh air from the atmosphere is adapted to be heated by the muffler before being discharged into the body of the automobile.

Another object is to provide a jacket of 10 this type that is cheap to manufacture and is easy to install and that will serve effectively to protect the muffler, especially during summer, by maintaining a circulation of 15 fresh air about the muffler so that the latter will be prevented from burning out or being otherwise damaged.

With the above and other objects in view, the invention resides in certain novel features of construction, combinations and arrangements of parts as will be more fully described and particularly pointed out in the appended claims.

In the accompanying drawing:

Figure 1 is a fragmentary side elevation 25 of an automobile with a heater embodying my invention applied thereto.

Figure 2 is an enlarged longitudinal vertical sectional view through the heater jacket and showing the muffler in elevation.

Figure 3 is an end view of the heater jacket.

Referring now to the drawing, the numeral 1 designates a jacket embodying my invention surrounding a standard type of exhaust muffler 2 of an automobile. As shown, air from the atmosphere is supplied to the forward end of the jacket 1 by a suitable pipe or conduit 3 and after being heated by the heat thrown off by the muffler 2 is delivered from the opposite end of the jacket into the body of the automobile by means of a suitable pipe or conduit 4. It is well known that mufflers are constructed to retard the flow of the exhaust gases from the engine so that the intense heat of the gases will be thrown off before the gases are discharged into the atmosphere, hence it will be apparent that the outer walls or casing of the muffler will receive this heat and will provide a large heating surface for the air within the jacket. Inasmuch as the jacket completely surrounds the muffler and receives the fresh air from the atmosphere in front of the muffler it will also be apparent 55 that the forward end of the muffler will

serve as a baffle for deflecting the air about the jacket and will thereby effectively retard the flow of air so that it will be heated thoroughly before being delivered into the body of the automobile.

In order that the jacket 1 may be manufactured cheaply and will be easy to install, it is preferably constructed of two complementary transversely curved sections 5 and 6 respectively which have segmental recesses 7 at the ends thereof for receiving the sections 8 and 9 respectively of the usual exhaust conduit and have marginal flanges 10 that are adapted to be bolted or otherwise secured together to hold the jacket into position. Inasmuch as certain types of mufflers have peripheral flanges such as 11 shown in Figure 2, the sections 5 and 6 are preferably provided adjacent to their opposite ends with the transversely extending laterally projecting channel-shaped portions 12 to permit the air to circulate longitudinally of the muffler 2 around these flanges and are also preferably provided with short metal straps 13 that extend across these channel-shaped portions for engagement with the flanges 11. Hence it will be apparent that the jacket 1 is applicable to various types of mufflers and that such application may be readily accomplished 80 without removing, substituting or otherwise changing the standard parts of the automobile.

While it is believed that from the foregoing description, the nature and advantage 90 of my invention will be readily apparent, I desire to have it understood that I do not limit myself to what is herein shown and described and that such changes may be resorted to when desired as fall within the 95 scope of what is claimed.

What I claim as my invention is:

1. In a heater for automobiles, a muffler having peripheral flanges, an air heating jacket including complementary sections adapted to surround said muffler in spaced relation thereto, said jacket having an internal diameter substantially equal to the diameter of the peripheral flanges and having enlarged channel-shaped portions surrounding said flanges, and metal strips bridging said channel-shaped portions and engaging said peripheral flanges.

2. In a heater for automobiles, a muffler having peripheral flanges, a jacket includ-

- ing complementary sections surrounding said muffler having an internal diameter substantially equal to the diameter of the peripheral flanges, a conduit connected to 5 said jacket in advance of said flanges for supplying fresh air from the atmosphere to one end of the jacket, said jacket having enlarged channel-shaped recesses adjacent the ends thereof surrounding said flanges 10 for permitting the passage of air longitudinally of the jacket from said conduit, and means bridging said channel-shaped recess and engaging said peripheral flanges.
3. In a heater for automobiles, a muffler having peripheral flanges, a jacket including complementary sections surrounding said muffler and having laterally projecting channel-shaped portions surrounding said 15 flanges, and means for securing said jacket in spaced relation to said muffler including 20 metal strips disposed between said flanges and channel-shaped portions.
4. In a heater for automobiles, a muffler having peripheral flanges, a jacket including complementary sections surrounding 25 said muffler having laterally projecting channel-shaped portions adjacent the opposite ends thereof cooperating with the peripheral flanges to form an air passage longitudinally of the jacket, and means engaging said channel-shaped portions and flanges for securing the jacket in spaced relation to the muffler.

In testimony whereof I affix my signature.

JAMES J. SUNDAY.
